METHOD OF MAKING SOUND RECORDS

Arthur C. Blaney, Los Angeles, Calif., assignor to
 Radio Corporation of America, a corporation of
 Delaware

Application January 30, 1939, Serial No. 253,613

7 Claims. (Cl. 274—46)

This invention relates to the production of motion picture sound records and particularly to the recording and printing processes involved in the making of such records.

The usual method for the production of motion picture sound records is to light-impress a film with light, varying transversely of the sound track portion of the film (variable area records), or varying in intensity (variable density records), in accordance with the form of the sound waves of the signal to be recorded. Noise reduction is usually applied to variable area records by shuttering off the light from the unused portions of the sound track area, and, is usually applied to variable density records by operating between one end of the density characteristic and the central point thereof.

For the purpose of description, reference hereinafter to "sound record" will mean a film sound record track as finally produced for reproduction in theatres, while a "negative record" will refer to a film sound record track from which a sound record is printed. The usual method of making sound records is to first make a negative record with the sound recording apparatus and then make a print for reproduction. Normally, therefore, the sound record is a print of a negative sound record. The present invention relates to recording systems whereby a final sound record is recorded directly with the recording apparatus and such a record will be called, for purposes of description, a "direct sound record."

Variable area recording systems for producing direct sound records are well known. This type of recording has many advantages over the negative method, inasmuch as it eliminates the printing step required as mentioned above. Another advantage is that noise reduction appears as opaque areas after the first development, thus eliminating the deleterious effects of dirt on the negative, while these areas may be exposed to a greater extent to provide greater noise reduction. It also has the advantage of permitting simplified anticipatory noise reduction, which permits the sound track area to be prepared in anticipation of the application of the signal, thus avoiding peak-clipping prevalent in systems where the noise reduction and signal are impressed at the same point on the film. Also, where only one copy is required, the cost of making a print is saved. Such a direct sound record recording system has been disclosed and claimed in copending application Serial No. 338,424, filed June 1, 1940, as a continuation of application Serial No. 168,173, filed October 9, 1937, and

assigned to the same assignee as the present application.

In the process of producing a final motion picture, the various shots made each day are reviewed by directors, actors, sound technicians and others. Several sound records are therefore required for this purpose. Also, additional records are usually required for the rerecording process wherein several tracks are combined to produce a composite sound track for the final picture. Thus, although the direct sound record recording system produces a record which may be immediately used, more than this one record is required. Ordinarily, to produce additional records it is necessary to first print a negative record from which other sound records may be subsequently printed. By these steps some of the advantages of the direct record system are lost, as there is still the opportunity for dirt to appear on the intermediate negative.

An object of the present invention, therefore, is to facilitate the production of sound records.

Another object of the invention is to make sound records directly from sound records in the normal developing process.

A further object of the invention is to eliminate the necessity of making a negative record from a sound record to obtain duplicate sound record prints thereof.

30 A further object is to make film prints from sound records without increasing the noise level of the original sound record.

Although the novel features which are believed to be characteristic of this invention are pointed out with particularity in the claims appended herewith, the manner of its organization and the mode of its operation will be better understood by referring to the following description read in conjunction with the accompanying drawing forming a part thereof, in which—

Figure 1 is a negative record of a duplex sound track;

Figure 2 is a sound record printed from the negative record of Fig. 1;

45 Figure 3 is a direct sound record; and

Figure 4 is a print made from the direct sound record of Fig. 3.

Referring now to Fig. 1, a negative record is shown of a sound track of the standard duplex type, wherein the sound modulations have a transparent area 5 and opaque areas 6, and noise reduction transparent areas 7. The opaque areas 6 are bounded by traces made in accordance with the signal modulations and the envelope of the signal modulations. Upon this negative is shown

a dirt spot 10, which, we may assume, is opaque and adherent to the transparent area 7 of the film.

Now, in printing the negative of Fig. 1, the sound record of Fig. 2 is the result, the dirt spot 10 appearing as a transparent image 10' in the opaque portion 12. In this print, of course, the transparent area 5 is now opaque area 13, and the opaque areas 6 are now transparent areas 14. It is well known that the dirt spot image 10', being transparent in an opaque area, will produce a "plop" or "click" according to its size, while a series of such images or "holes" will of course produce hissing, or one form of ground noise. It will also be seen that although the sound record in Fig. 2 may be used for reproduction of the sound track, it was necessary to go through the steps of developing the negative, printing, and developing the print to produce such a record. Each of these steps not only increases the noise level, but is also accompanied by a definite loss in quality. Thus the elimination of any of these steps is a decided advantage. Several prints, of course, may be made from the negative of Fig. 1 for review room and rerecording purposes, while the result of the rerecording process produces a master negative from which the sound records for the picture are printed.

Now, in Fig. 3, there is shown a direct sound record with a track of the standard duplex type shown in Figs. 1 and 2 and which may be made with the apparatus disclosed and claimed in the above-identified copending application. This record is suitable for reproduction and is seen to have the same relative opaque and transparent areas as the record of Fig. 2. The dirt spot 10 also appears on this sound record, but, being opaque and occurring in the opaque portion of the sound track area, it causes no deleterious effect or extraneous noise. Although there may be a slight variation in density between the area of the dirt spot and the remainder of the opaque portion 16, it is insufficient to create any effective light differential in the photocell. This result, of course, is attributable to the direct record system such as disclosed in the above-identified copending application.

However, as mentioned above, more than one print is required in the normal production of the motion picture for which the sound record is required. Normally, additional records would be produced by printing a negative from the record of Fig. 3, which would appear as shown in Fig. 1, from which other sound record prints may be made. There are added two printing steps, two developments and one film. The present invention eliminates one of these printings, one of the developments and the negative film. To accomplish this, a sound record print as shown in Fig. 4 is made directly from the direct sound record. This single printing may be carried out by two methods. One is to subject the printed stock to the well known amateur film reversing process, although this process is not preferred, since it is not adaptable or suitable to motion picture studios or commercial motion picture laboratories where the special reversing developer is not usually available. Furthermore, this special process is comparatively expensive and complicated. The preferred method of the invention, therefore, accomplishes the result by the use of a direct copy emulsion stock now being manufactured by Eastman Kodak Company and named "auto-positive" and in which the reversing has been done before exposure and which thus only requires the usual

type of normal development now in commercial studio and laboratory use. This method will produce a sound record print from a direct sound record or a negative print from a negative.

5 Thus, no change in commercial processing is required.

All that is required for the preferred method, therefore, is to originally record as a direct sound record, subject this negative or direct sound record to the usual commercial processing (not reversal process), which results in a record such as shown in Fig. 3, then print the direct record in a contact or optical printer to the auto-positive stock, and then subject this printed stock to the 10 normal commercial developing process (not reversal process) in use in commercial laboratories or in studios where processing is done.

The direct sound record of Fig. 3 may, therefore, serve as a negative for printing purposes

20 and from which as many duplicate sound records as desired may be made. In the making of such duplicates in accordance with the invention, all the advantages of direct sound record recording are retained. For instance, the dirt spot 10 of 25 Fig. 3 now appears in the record of Fig. 4 as an opaque image 10'' in the opaque noise reduction area 17. Also, there is no negative film required on which dirt will produce holes in the opaque areas of the final print. Thus, the duplicate 30 prints not only may be made directly from the direct sound record used as a negative, but this method has the advantage over negative printing of eliminating noise caused by dirt on the direct positive which would cause noise if on a negative. 35 Also, by the use of the direct copy emulsion for printing from a direct sound record, all the other advantages attributable to, and inherent in, the direct record method of recording are retained, such as anticipatory noise reduction, saving 40 in time and film, etc.

Although the above invention has been disclosed as embodied in a variable area sound track of a specific type, it is to be understood that all the advantages thereof are also attendant 45 upon its use for other types of variable area tracks as well as in variable density systems. It is also to be understood that this printing process is applicable to the making of additional copies of sound record prints from sound record 50 prints made from negatives such as shown in Fig. 2. Thus, a first print used as a negative may provide cleaner duplicates than the original negative after several prints have been made from the latter.

55 I claim as my invention:

1. The method of producing a sound film track record comprising light-impressing a normal negative film in accordance with sound waves to be recorded, said light impression and the normal development of said film producing a positive record of said sound waves, light-impressing a second film with the light variations produced by said positive film, and reversing by development of said second film to produce a positive duplicate of said first film.

2. The method of making sound film track records comprising recording a direct sound record from the signal being recorded, normally processing said record, said recording and said 70 processing producing a positive sound track record, exposing a direct copy emulsion film stock in accordance with the light variations of said positive record, and normally developing said stock to produce an exact duplicate of said direct sound record.

3. The method of making sound film track prints comprising the step of exposing a normal negative film emulsion so that upon normal development thereof a positive record is produced, exposing a plurality of direct copy emulsion films to light variations produced by said positive record, and normally developing said direct copy emulsion films in the same manner as said first film.

4. The method of making a plurality of sound film track prints of a certain signal comprising modulating light with said signal and light-impressing a normal negative film emulsion so that upon normal development thereof a positive record of said signal is produced, exposing an auto-positive stock to light variations corresponding to said positive record, and subjecting said stock to the same development given said first film.

5. The method of producing a sound film track record comprising light-impressing a normal negative film in accordance with a signal, normally developing said film to produce a record of said signal, the variations in light impressed

upon said film being such as to produce a positive sound record of said signal, exposing a second film to variations in light produced by said first record, and normally developing said second film to produce a duplicate of said direct sound record.

6. The method of producing a plurality of sound film track records comprising recording a negative sound record, printing a positive sound record from said negative, exposing a plurality of films of direct copy emulsion film stock to light variations in accordance with said positive sound record, and normally developing said films to produce duplicate positive films.

7. The method of producing a sound film track record comprising the steps of light-impressing a normal negative film in accordance with sound waves to be recorded, producing from said light impression and the normal development of said film a positive record of said sound waves, and light-impressing a second film with the light variations produced by said positive film record and directly producing a positive duplicate of said first film.

ARTHUR C. BLANEY.
